UNITED STATES PATENT OFFICE.

WILLIAM F. NIES, OF BIDDEFORD, MAINE.

FERN-DISH, JARDINIÈRE, OR SIMILAR RECEPTACLE.

1,087,546.

Specification of Letters Patent.

Patented Feb. 17, 1914.

Application filed August 16, 1912. Serial No. 715,341.

To all whom it may concern:

Be it known that I, WILLIAM F. NIES, a citizen of the United States, residing at Biddeford, county of York, State of Maine, have invented an Improvement in Fern-Dishes, Jardinières, or Similar Receptacles, of which the following description, in connection with the accompanying drawing, is a specification, like characters on the drawing representing like parts.

This invention relates to receptacles suitable for use as fern dishes, jardinières, etc., and has for one of its objects to provide a novel receptacle of this nature which is made directly from a block of wood having the bark thereon so that the outer wall of the article is formed of the bark of the tree, and which has such a construction that the bark will not crack or split by reason of any expansion or contraction of the wood due to changes of temperature.

Referring to the drawings wherein I have illustrated an embodiment of my invention, Figure 1 is a view of a block of wood from which one of my improved receptacles can be made; Fig. 2 is a vertical central section through the completed receptacle; Fig. 3 is a perspective view of the receptacle completed; Fig. 4 is a bottom plan view of the completed receptacle; Fig. 5 is a section on the line $x-x$, Fig. 2; Fig. 6 is a perspective view of the block of wood shown in Fig. 1 after the heart has been removed.

In making a dish or receptacle embodying my invention I take a block of wood 1 having the bark thereon and first remove the center so as to leave a band or cylinder comprising merely the sap of the block of wood with the bark, and then I insert a metal lining 7 to the ring or band and secure it thereto. The block of wood 1 will be selected of the proper size for the receptacle and will be cut to a length equal substantially to the depth of the desired receptacle. The heart 4 of the block of wood is cut out by means of a band saw, thus leaving a cylindrical member formed of the sap and bark of the block, as seen in Fig. 6. In thus sawing out the center, I propose to saw into the side of the block along the dotted line 2 and then to saw around on the dotted line 3 to cut out the heart 4. This leaves a split band 5, such as shown in Fig. 3, composed of the sap and the bark 6. A lining 7 of metal is then inserted into the split band 5, said lining being

made of sheet metal formed into the desired shape and size. The opening in the split band 5 is flared slightly at the upper end, as shown at 8, and the upper edge 9 of the lining 7 is preferably flared outwardly to fit 60 the flared portion 8.

The receptacle is completed by applying to the top and the bottom thereof hoops or bands 10 and 11. These hoops not only provide a finish to the article, but they also 65 are means for assisting in permanently uniting the lining 6 to the wooden exterior 5. In order that the hoops 10 and 11 may fit tightly I will preferably turn down the wooden exterior 5 at its ends, as shown at 70 12, thus providing a smooth perfectly cylindrical surface on which the hoops 10 and 11 may be driven. Each hoop is secured to the lining 7 and while this end may be accomplished in a variety of ways I have herein 75 shown the hoop 10 as turned over at its upper end to form the beading 13, and this turned-over portion or beading meets the upper edge 9 of the receptacle 7 and may be permanently secured thereto by solder 80 or any other suitable means. The lower end of the receptacle is preferably provided with a plurality of notches 14 and connecting members 15 are employed in the notches for rigidly connecting the bottom of the lining 85 7 to the hoop 11. These connecting members 15 may be in the nature of blocks of solder or any other material which will permanently adhere to both the lining and the hoop. I have shown a felt cover 16 secured 90 to the bottom of the receptacle so that it will not mar a table or other polished article of furniture.

The hoops 10 and 11 serve to hold the exterior band 5 of wood onto the lining 7 and 95 prevents said band from opening away from the lining. Moreover, by connecting one hoop to the lining at the top thereof, and the other hoop to the lining at the bottom thereof, the lining is firmly held in the 100 wooden exterior. The wooden exterior 5 is in the nature of a split band, that is, it is a band which is split longitudinally at the point 2 where the band saw enters the block of wood. The advantage of this construction is that the exterior 5 will not become cracked or checked due to any swelling or shrinking action which takes place in the wood in atmospheres having different degrees of humidity. If there is any tendency 105 110

for the wood to swell or shrink the split in the wooden band will permit such tendencies without danger of cracking the wood.

Having fully described my invention, 5 what I claim as new and desire to secure by Letters Patent is:—

In a device of the class described, the combination with a metal lining, of an envelop therefor comprising a band of wood split 10 diagonal thereof with the bark thereon, said band having a reduced diameter at its top and bottom edges to form hoop receiving portions and provided at its lower end with a plurality of notches, a hoop encircling each

of said portions, the upper edge of the top 15 hoop being bent to present a bead which is connected to the top edge of the lining and means entering said notches and rigidly connecting the bottom edge of the bottom hoop to the bottom of the lining.

20 In testimony whereof, I have signed my name to this specification, in the presence of two subscribing witnesses.

WILLIAM F. NIES.
